FRAMING-TOOL.

1,145,311.

Specification of Letters Patent.

Patented July 6, 1915.

Application filed May 6, 1913. Serial No. 765,798.

To all whom it may concern:

Be it known that I, ALFRED HOLMBERG, a citizen of the United States, residing at Central Falls, in the county of Providence 5 and State of Rhode Island, have invented a new and useful Improvement in Framing-Tools, of which the following is a specification.

My invention is an improved framing tool 10 which combines in one implement the functions of a square, a bevel and a slide rule.

The purpose of my invention is to provide a single tool which at one setting shall determine the angles of different cuts and 15 shall be available, also at one setting, for marking out both right and left hand cuts; and which by suitable scales arranged co-ordinately with the adjustable elements of the device shall enable the worker to read 20 directly from the setting of the tool data which is usually the subject of computation or reference to computed tables, such as the lengths of rafters, jack rafters and the like.

Of the accompanying drawings forming 25 a part of this specification:—Figure 1 is an elevation showing my improved tool as used for laying out framing cuts; Fig. 2 is a conjoined view of both front and back of the blade at the graduated portion showing how 30 the data referred to is read direct from the position of the slide which determines the position of the adjustable tongue; Fig. 3 is a detail view, sectional of Fig. 1 on the line *a*—*b*, looking in the direction of the 35 arrow *c*. Fig. 4 is a detail view sectional of Fig. 1 on the line *d*—*e* looking in the direction of the arrow *f*. Fig. 5 is a perspective view of a part of the lower hinge. Fig. 6 is an enlarged detail view of the graduated 40 index for adjusting the two sections of the device in intersectional relation. Fig. 7 shows the range of swing of the coördinate bevel device. Figs. 8 and 9 show the tool with the auxiliary bevel section removed 45 and replaced by the straight edge, for use as a square, Fig. 8 being a plan view.

Referring to Fig. 1 and to Fig. 3, the blade 2 is of rectangular section and to this blade is hinged the tongue 3 at the point 4, 50 the tongue being of deep channel section and embracing the blade 2 at the hinge point. The tongue 3 can be set square with the blade 2 and in this position the tool is used as an ordinary square as will be later 55 explained, but the prime purpose of the

tongue in framing work is to lay out the plumb cuts of rafters, both for common rafters and for "hip" and "jack" rafters.

The tongue 3 is adjusted with relation to the blade or body 2 by means of the slide 5 which is connected with the tongue 3 by the link or brace 6, and is locked to the blade in any given position by a suitable device such as the set screw 7. The slide 5 is held to the blade 2 and guided thereon by 60 any suitable provision such as the shoe or slide 9 which is secured to the slide 5 and is movable in the slot 8 in the said blade. The slot 8 terminates at the bottom at a point such that when the slide 5 is in its 65 lowermost position the tongue 3 is exactly 70 square with the blade 2.

In the bottom of the tongue 3 is a sliding bar 10, the function of which is to extend the bottom edge of the tongue to the edge of the 75 stick being marked when the tongue 3 is out of "square" with the blade, so as to accurately locate the beginning of the cut, and without having recourse to a straight- 80 edge or to another bevel square or other im- 85 plement. The bottom of the tongue 3 is cut away at 11 (best shown in Fig. 9, and in Fig. 1 in the broken line representation of the tongue denoted by 3^x). The extremity of the bar 10 is of flanged or T section, the 90 flanges 12 corresponding with the "jog" or cut away portion of the tongue 3, and the bottom of the flanged portion is flush with the bottom of the tongue. The bar 10 is held against the bottom of the tongue by the 95 end of the blade 2 and by the lock 14.

The lower end of the blade 2 is curved concentric with the hinge or joint pin at 4, and in the curved edge are formed teeth 50 which mesh with corresponding teeth 51 in 95 the top of the bar 10, which teeth, by their intermeshing lock the bar against longitudinal movement. To adjust the bar in position the tongue 3 is closed against the blade 2 as indicated at 3^y by broken lines in Fig. 1, in which position the teeth 51 of the bar 10 are withdrawn from the teeth 50 of the blade 2. The bar is then pulled out to a position such that when the tongue as in its 100 adjusted position the bottom of the flanged 105 extremity of the bar will intersect the edge of the stick to be marked.

The lock 14, better shown in Fig. 4 is a block which rests on top of the bar 10 and in a rectangular hole in the side of the 110

tongue 3. At its top, the block 14 has a beveled flange 15 which abuts the beveled edge 16 of the hole in the tongue side in which it lies. Engaging the block is a screw 17, which, when tightened, draws the beveled flange 15 into engagement with the beveled edge 16, thus forcing the block down upon the bar 10 and holding the latter against the bottom of the tongue. Preferably a countersink head screw is employed and the countersink in the tongue side is slightly nearer to the top of the bar 10 than is the screw 17 so that the head of the latter cannot seat fairly, but its tendency to so seat causes it also to exert a wedging effect upon the block. In Fig. 1 the tongue 3 is shown in broken lines at 3° set at "miter" or at 45 degrees, and the bar 10 is shown projected to meet the edge of the stick being marked, the flanged extremity of the bar being indicated at 12° .

On the edge of the blade 2 opposite that on which the slide 5 travels are two hinge portions 18 and 19, preferably separate pieces secured to the blade. By these hinge portions or sections there is joined with the blade a coördinate bevel device whose function is to determine the angle of the horizontal cuts, corresponding with the plumb cuts determined by the tongue 3, for jack rafters and for "hip" and "valley" rafters. This coördinate bevel device consists of a blade 20 having hinge portions 21 and 22 corresponding and engaging with the hinge portions 18 and 19 respectively, and also an adjustable tongue and means to adjust the same just as the tongue 3 is adjusted.

The hinge part 18 consists of a rectangular sleeve or collar, secured in position by the set screw 23. On the end opposite to the set screw are the lugs or ears 24 which receive the pin 25, which pin may be made with a knurled head to facilitate removal. The connecting hinge part 21 is of similar form, receiving the upper end of the blade 20, which is secured in position by the set screw 29. The entire coördinate bevel device is thereby adjustable longitudinally of the blade 2 so that its adjustable tongue 30 can be set with the line of its bottom or marking edge intersecting the line of bottom or marking edge of the tongue 3. To facilitate this adjustment, the blade 20 is graduated as shown in Fig. 6, each graduation corresponding with one of the pitch graduations on the blade 2. Two lines of graduations are provided, one for "hip" and "valley" rafters and one for jack rafters. The graduations are marked with the corresponding pitches so that, to insure that a horizontal cut shall properly intersect with the corresponding plumb cut, it is only necessary to set the blade 20 at the graduation at P which reads with the same pitch number as that at which the slide 5 is set on the

blade 2—Fig. 6. The lower hinge part 19 is of a known construction to avoid a removable pin. This is accomplished—see Fig. 5—by making the two pin lugs 26—26 in the shape of opposed U's. The pin 27 is 70 tightly secured to or integral with the hinge portion 22. To connect the two hinge portions, the part 22 with its connected blade 20 is inclined from the plane of the main blade 2 sufficiently to permit the pin 27 to 75 pass the ends 28—28 of the U shaped lugs 26—26, the ends being cleared by beveling to admit the pin. The hinge portion and blade are then righted into the plane of the blade 2 which brings the hinge part 21 into 80 engagement with the lugs 24—24 to which it is secured by the pin 25. To permit the above described adjustment of the coördinate bevel device, the lower hinge part 22 is not rigidly secured to the blade 20 but is 85 slidably connected therewith by the shoe which runs in the slot 33 of the blade secured to the slide by the screw 32, just as the slide 5 is mounted slidably on the blade 2. A third slide 34 is similarly mounted on 90 the blade 20, which slide is connected with the tongue 30 by the link or brace 35, and determines the position of the said tongue for any side cut on jack rafters and on "hip" and "valley" rafters. A shoulder 95 31 limits the downward movement of the slide 34, to a position in which the corresponding position of the tongue 30 is 45 degrees with the blade 20 or set for a mitering cut. 100

The graduations at S serve a kindred purpose to those already described. They are marked to correspond with the pitch graduations on the blade 2, and with the same numbers, although the scale of the drawing 105 does not admit their being shown. The graduations are in two lines the same as the graduations at P, one line being for jack rafters and the other line for "hip" and "valley" rafters, and the slide 34 is marked 110 to denote the class of rafters to which each line pertains, H & V denoting "hip" and "valley" rafters, and Jack denoting jack rafters.

This is the manner of using the tool in 115 marking out for example a "hip" rafter. If it be desired to cut such a rafter for a $\frac{1}{4}$ pitch roof, which is a roof pitching 8" per foot, the slide 5 should be set to 8 in the line of figures opposite the words Hip— 120 Valley on the slide 5, and the slide 34 should likewise be set to the graduation marked 8 in the line of graduations opposite the letters H & V on said slide—at S. This establishes the angles of the plumb and horizontal cuts desired. Where, as in the case of common rafters and the feet of "jack" rafters, the cut is ascertained by only one slanting line across the side of the stick, the other line of cut being "square" across the 125 130

stick's edge, the cut is referred to as a "plain cut"; and where, as in the case of "hip" rafters and "valley" rafters, and in the case of the upper ends of "jack" rafters, 5 the cut is determined by two slanting lines, one aslant the edge of the stick and the other aslant the side of the stick, such a cut is termed a "compound cut." Obviously the main section alone is sufficient for laying out 10 "plain cuts," but the combination of the main section with the coördinate device provides for simultaneously laying out both cuts and for uniformly laying out a succession of such cuts. Note that the two 15 slides 5 and 34 "read by," or register with the appropriate graduations by their top edges. Having determined the angles of the cuts, their lines of cut are made to intersect in the manner already described by reference 20 to the graduations at P, which graduations, it should be noted are to be read from the bottom edge of the hinge part 21. It is to be also understood that the bar 10 is run out of the tongue 3 to reach the edge 25 of the stick being marked and determine the point for starting the cut.

Referring to the tool as a slide rule for ascertaining measurements which are usually computed or ascertained from independent tables, this feature will be explained with reference to common rafters and the settings therefor. When the tongue 3 is set for any given pitch it is to be noted that its "reading" or top edge registers 30 with graduations of three individual rows of graduations on the front face of the blade 2, and with all of the graduating lines of the tabulation on the reverse or back of the blade—see Fig. 1 and Fig. 2. This 35 tabulation gives the lengths of common rafters for any given run or half width of building indicated by the figures at T. From the scale of runs given, lengths of rafter for runs not stated can be readily ascertained 40 by adding two or more lengths determined from the scale. Therefore, having set the tool for a given pitch of common rafter the length of that rafter is read directly from the graduated scale of lengths. In the position 45 of the blade 3 denoted by the broken lines at 3° , the slide 5 reads at 12 in the scale of pitch for common rafters found on the face of the blade 2. Turning the tool over the length of rafter for a building 20 ft. wide is found in the row of graduations 50 for a 10 ft. run (10 ft. being half the width of the building) as 14 ft.— $1\frac{1}{2}$ in., the notation being in 12ths.

If the roof is to have either "hip" or 60 "valley" it is necessary to ascertain the lengths of the jack rafters. These are spaced either 16 in. on centers or 2 ft. and the first jack rafter is located from the starting point—either the plate or intersection with 65 the roof of the ridge which forms the val-

ley—the distance of the spacing, *i. e.* either 16 in. or 2 ft. Consequently the lengths of all jack rafters after the first are multiples of the length of the first jack rafter. Therefore it is necessary to indicate only the 70 length of the first jack rafter, and these lengths are found in the rows of figures opposite the formulas J. R. 16 c—c and J. R. 2 ft. c—c, which appear on the slide 5. Having determined the angle of the plain cut and the 75 lengths of the jack rafters, the compound cuts are laid out in the same manner as are those for a "hip" rafter, only the slide 34 is set by the graduations marked Jack and the intersection of the plumb and horizontal 80 cuts is determined from the corresponding line of graduations at P. For the purpose of convenient and concise statement in the claims, the lengths of common rafters and kindred derivatives of the pitch will be 85 termed functions of the pitch. But jack rafters are cut "rights" and "lefts" which is accomplished with my improved tool without change of setting, and hence with greater accuracy. The hinges which connect the coördinate bevel device with the blade 2 permit 90 the device to swing through a range which includes positions 180 degrees apart in either of which positions the device is "square" with the plane of the main section. This is shown in Fig. 7, where the full lines show the blade 20 at right angles or "square" with the plane of the main blade 2 in one position, while at 20° it is shown in the opposite position or swung 95 through 180 degrees, where it is again "square" with the plane of the blade 2. As indicated at 20° the coördinate bevel device can be swung through an extent exceeding 180 degrees.

In case a square only is desired, the coördinate bevel device may be removed and replaced by a straight edge 40 as shown in Fig. 8 and Fig. 9. Referring to Fig. 8, the straight edge 40 is of channel form fitting the blade 2, and having flanges 41—41 which constitute the shoulders which lie against the stick to be marked. Obviously the flanges 41—41 must be straight and true, and to maintain this condition the straight 110 edge must fit the blade 2 snugly. It is fastened to the blade 2 by two pins or fixed tongues 43 and 44, one of which engages the lower hinge part 19, the body of the straight edge being cut away at 42 to admit the hinge 115 part 19, and the other being engaged by the hinge part 18. Application of the straight edge is preferably effected by first removing the member 18 from the blade 2. The straight edge is then applied to the blade 2, the hinge part 19 passing through the aperture 42. The straight edge is then slid downward engaging the pin 43 with the hinge lug 26. Then the hinge portion 120 18 is applied to the blade 2, being slipped 125

downward until its lower lug 24 receives the pin 44 and bearing upon the lug 45 holds the straight edge tightly against the hinge portion 19, the hinge portion being secured to the blade 2 by its set screw.

I am aware that there are implements which have graduations by which an adjustable blade can be set to different pitches, and that there are others on which are imprinted scales of dimensions and the like, but my device is to be distinguished from such in that it provides for reading such data direct from the index or reading edge of the slide which controls the position of the main tongue 3; in that both right and left cuts can be made at one setting without readjustment; and in that it supplies means for extending the marking edge of the adjustable tongue to the edge of the stick 15 where the cut must start, as well as other features that have been brought out.

It is obvious that other graduations than those described can be supplied and that those described or shown can be amplified. 25 The scale of graduations 55 on the blade 2, and opposite the formula "L of H & V per ft. run" on the slide 5, gives the length of "hip" and "valley" rafters per foot of run, but it is obvious that by enlarging the 30 area of the blade 2 or by employing finer figures a scale similar to that for common rafters can be supplied enabling the lengths for different pitches to be read direct from the index edge of the slide 5. Again, a 35 scale of graduations at 56 gives the settings necessary to secure the correct angles of cut for various polygonal shapes such as the square, pentagon, hexagon and others. 40 Again, it is possible to introduce modifications of construction and arrangement without departing from the spirit of my invention, and

Therefore, without limiting myself to the precise form and arrangement described I 45 claim:

1. In a framing tool, the combination with two bevel devices, each comprising a graduated blade, an adjustable tongue, a slide movable on the blade and registering with 50 the graduations to determine the adjustment of the tongue, and connections between the tongue and slide, of hinges to connect the two bevel devices to permit them to swing, one with relation to the other.

55 2. In a framing tool, the combination with a blade, a tongue adjustable on the blade, and means to secure such adjustment, of a bar projectable from the tongue and having a portion 12 with a face that is flush with the bottom of the tongue, and means to lock the bar in position.

60 3. In a framing tool, the combination with two bevel devices, each comprising a graduated blade, an adjustable tongue, a slide movable on the blade and registering with

the graduations to determine the adjustment of the tongue, and connections between the tongue and the slide, of separable hinges to connect the two bevel devices.

4. In a framing tool, the combination with 70 an adjustable tongue, of a blade with respect to which the tongue is adjustable, the said blade having a graduated index of pitches and, in line with each pitch graduation, appropriate readings giving functions 75 of that pitch, a slide having a reading edge which, when set at a given pitch graduation reveals at said reading edge the appropriate readings for functions of that pitch, and means to connect the tongue with the 80 slide.

5. In a framing tool, the combination with a blade graduated with different pitches, and having in line with each pitch graduation readings of function appropriate to 35 that pitch, and a tongue adjustable to the cutting angles for the pitches indexed, of a slide having an index edge which, when the tongue is set at the angle appropriate for a given pitch, registers concurrently with 90 the graduation for that pitch and with the functional reading appropriate to the same, and means to connect the slide and tongue.

6. In a framing tool, the combination with 95 a main section, a coördinate device hinged to the main section and movable through a range which includes two opposite positions in each of which positions it is square with the plane of the main section and hinges to connect the main section with the coördinate 100 device, the said hinges being so connected on the coördinate device as to permit longitudinal adjustment of the coördinate device with reference to the main section.

7. In a framing tool, the combination with 105 a tongue, a hinge pin therefor and a blade with reference to which the tongue is adjustable to which the hinge pin connects the tongue, the said blade having a portion of its edge concentric with the hinge pin and 110 formed with teeth, of a bar mounted within the tongue and having teeth to engage those of the blade in the manner and for the purpose specified.

8. In a framing tool, the combination with 115 a tongue, a hinge pin therefor and a blade with reference to which the tongue is adjustable and to which the hinge pin connects the tongue, the said blade having teeth, of a bar mounted within the tongue and having 120 teeth which engage the teeth of the blade when the tongue is in working position, and which are disengaged from the teeth of the blade by swinging the tongue beyond its normal range of movement.

9. In a framing tool, the combination with 125 a blade and a tongue thereon adjustable with respect to the blade and having an opening with beveled edges, of a projectile bar carried within the tongue, and a block 130

- seated in said opening in the tongue having a beveled portion engaging said beveled edge of the opening, and means to cause said block, through such engagement, to act with locking effect upon the bar.
10. In a framing tool, the combination with a blade, a tongue having a beveled edged opening, a projectile bar within the tongue and means to connect the blade and tongue, of a block within the opening of the tongue having a beveled portion to engage the beveled edge of the opening and a screw to engage the beveled portion of the block with said beveled edge to force the block upon the bar as described.
11. In a framing tool, the combination with a blade, a tongue mounted on and adjustable with respect to the said blade, a slide to determine the position of the tongue, means to secure the slide, and connections between the slide and the tongue, of interchangeable line determining devices attachable to one edge of the blade, and means to interchangeably attach the said devices.
- 20 12. In a framing tool, the combination with a main section and a coördinate section, of a hinge to connect the two sections, one portion of which hinge is slidable on the main section and one portion slidable on the coördinate section, and a second hinge to connect the two sections, one portion of which hinge is fixed to the main section and the other portion of which is slidable on the coördinate section.
- 30 13. In a framing tool, the combination with a main bevel section and two hinges, one hinge comprising a slide with a reading edge, of a coördinate bevel section attached to the main section by the two hinges, slideable with respect to the two hinges, and bearing graduations that register with the reading edge of the said hinge, the said graduations serving to determine that relative position of the sections which shall set 40 45 cure intersection of the lines established by them.
14. In a framing tool, the combination with a main section comprising an adjustable tongue, a blade with a graduated index of pitches thereon, a slide having an index edge to register with said graduations and means to connect the tongue and slide, of a coördinate section comprising a blade 20 bearing two sets of graduations, one set P 50 55 to determine the longitudinal relation of the two sections and the other set S to determine angles of cut to be laid out by the coördinate section, a connecting device to join the two sections having an index edge that registers with the graduations for longitudinal relation, a slide 34 having an index edge to register with the graduations for angle of cut and movable on the blade 20, a tongue 30 60 65 adjustably mounted on the blade to establish the line of cut determined by the slide 34 from the graduations and means to connect the tongue 30 and the slide 34.
15. In a framing tool, the combination with a blade having a graduated index of pitches for common rafters and for "hip" 70 rafters on one face, together with scales reading to lengths of "jack" and "hip" rafters for each pitch in line with the graduation for that pitch, and on the reverse side of the blade a scale with readings for the 75 common rafter lengths appropriate to each pitch and for different runs, the length for each pitch being in line with the graduation for that pitch, of a slide embracing the blade, one edge of the slide on each side of the blade 80 being a reading edge and both reading edges registering with the scale readings appropriate to a given pitch when the slide is set to the graduation for that pitch, an adjustable tongue mounted on the blade, and means 85 to connect the slide and tongue.
16. In a framing tool, the combination with a blade having a graduated index of pitches and graduations on both sides of the blade reading to functions of the pitch, of a slide embracing the blade, one edge of the slide on each side of the blade being a reading edge and both reading edges registering with appropriate readings of function for a given pitch when one edge is set at the 90 95 graduation for that pitch, and an adjustable tongue mounted on the blade, and means to connect the tongue and slide.
17. In a framing tool, the combination with a blade having a graduated index of 100 pitches and a scale reading to the rafter lengths for each pitch and for different runs of rafter, the lengths for each pitch being in line with the graduation for that pitch, of a slide having a reading edge which when 105 set at a given pitch graduation registers with the rafter lengths appropriate to that pitch, the said slide bearing readings indicating different runs of rafter.
18. In a framing tool, the combination 110 with a blade having a graduated index of pitches and scales reading to functions of the pitch, the readings for a given pitch being in line with the graduation for that pitch, of a slide having a reading edge which 115 when set at a given pitch graduation registers with the readings of function appropriate to that pitch, and bearing index readings to show the nature of the function-readings found at its index edge, and an adjustable tongue mounted on the blade and connections between the slide and tongue.
19. In a framing tool, the combination 120 with a blade having graduations, a hinged tongue angularly adjustable with respect to 125 the blade, a slide registering with the graduations to determine the position of the tongue, and means to connect the slide and tongue, of a coördinate device also comprising a blade, a tongue, a slide and means con- 130

necting the tongue and slide, means to connect the coördinate device with the blade first named, said connecting means including a third slide through which the blade of the coördinate device passes, the said blade having graduations that are correlated with the graduations on the blade first named to establish the intersection of the lines established by the two tongues.

10 20. In a framing tool, the combination with a main bevel device for determining the plumb cuts of rafters and graduated to secure the appropriate adjustment for any pitch, and a second bevel device for determining the horizontal cuts, and also graduated to secure the requisite adjustment therefor, of hinges to connect the two devices, the said hinges permitting the second bevel device to swing through 180 degrees, 15 at each extreme of which swing it is square with the main device.

21. In a framing tool, the combination with a blade, a tongue mounted on the blade and adjustable with reference thereto, a 25 movable device and hinge parts on the blade for connecting the removable device with the blade, of a straight edge held to the blade by said hinge parts, the straight edge and removable device being interchangeable, and 30 means on the straight edge to connect with said hinge parts.

22. In a combination framing tool, the combination with a main bevel device comprising a blade, a tongue thereon and adjustable therewith, and hinge parts on the blade, of a coördinate bevel device comprising a blade, a tongue and hinge parts to engage the hinge parts on the blade of the main bevel device, and a straight edge and parts 35 40 thereon to engage the hinge parts on the blade of the main bevel device, the coördinate bevel device and the straight edge being interchangeably connected with the main bevel device.

45 23. In a combination framing tool, the combination with a blade, an adjustable tongue thereon, a hinge part fixed to the said blade and a second hinge part movable on said blade, of a straight edge formed to 50 embrace the edge of the blade, and pins carried by the straight edge engaging the hinge parts aforesaid to connect the straight edge and blade.

55 24. A straight edge for a combination framing tool comprising separable coördinate bevel devices and means to connect said devices, said straight edge consisting of a channel portion, lateral flanges 41-41 and 60 connecting means aforesaid carried by one of said devices, to interchangeably replace the other device.

25. A straight edge to interchange with

one of two sections of a combination framing tool, each section comprising a blade, a tongue and hinge parts to connect the two sections, the said straight edge consisting of a body of channel form to fit the edge of the blade of the section to which it is applied, and having an opening 42 to receive one of the said hinge parts, and having also projections 43-44 to engage the said hinge parts.

26. In a combination framing tool, the combination with a bevel section comprising a blade, a tongue adjustable with respect to the blade, and means to secure the tongue in any position to which it may be adjusted, of a swingable, coördinate bevel device and hinge parts thereon for hanging it to the blade of the bevel section, a non swingable straight edge and means for attaching the same rigidly to the blade aforesaid, and hinge parts carried by the blade aforesaid to engage the hinge parts of the swingable, coördinate bevel device and also the attaching means of the straight edge, the said swingable, coördinate bevel device and straight edge being interchangeably applied to the blade aforesaid.

90 27. In a framing tool, the combination with a main bevel device comprising a blade a tongue mounted on the blade and angularly adjustable with relation thereto, and hinge parts mounted on the blade, of a coördinate bevel device comprising a blade and a tongue mounted on and angularly adjustable with relation to the blade of the coördinate bevel device, and hinge parts mounted in variable positions on the said blade of the 100 said coördinate bevel device, corresponding with the hinge parts on the blade of the main bevel device, the main device and the coördinate bevel device being joined and adjustably connected by the said hinges, and a straight edge of channel form conformed to the edge of the blade of the main bevel device, and having flanges, and projections corresponding with and to engage the hinge parts on the blade of the main bevel device, 110 the said straight edge and the said coördinate bevel device being interchangeable in their connection with the main bevel device.

105 28. In a framing tool, the combination with a blade and a tongue thereon, angularly adjustable with respect to the blade, of a bar movable longitudinally within the tongue and means whereby it is operated by the blade to impart such longitudinal movement.

110 In testimony whereof I affix my signature in presence of two witnesses.

115 ALFRED HOLMBERG.
